UNITED STATES PATENT OFFICE

2,174,621

APPARATUS FOR THE CONTROL OF HIGH-WAY CROSSING SIGNALS

Paul H. Crago, Wilkinsburg, Pa., assignor to The Union Switch & Signal Company, Swissvale, Pa., a corporation of Pennsylvania

Original application April 30, 1938, Serial No. 205,301. Divided and this application February 23, 1939, Serial No. 257,825

3 Claims. (Cl. 246—125)

My invention relates to apparatus for the control of highway crossing signals, and more particularly to apparatus for the control of highway crossing signals for electric railways.

5 The present application is a division of my co-pending application Serial No. 205,301 filed April 30, 1938, for Apparatus for the control of highway crossing signals.

A feature of my invention is the provision of novel and improved highway crossing signal control apparatus wherewith a loss of protection due to a temporary failure of power is avoided. Other features and advantages of my invention will appear as the specification progresses.

15 I shall describe one form of apparatus embodying my invention, and shall then point out the novel features thereof in claims.

The accompanying drawing is a diagrammatic view of a preferred form of apparatus embodying my invention.

Referring to the drawing, the reference characters 'a' and 'b' designate the track rails of a stretch of single track electric railway which is provided with a propulsion current supply conductor 2, such as a trolley wire or third rail, adaptable to contact by a suitable train carried current collecting device, such as a trolley wheel or third rail shoe not shown. In accordance with usual practice, the conductor 2, when a trolley wire, is supported substantially above the center line of the track at the necessary height. To aid in describing my invention, I shall assume the conductor 2 to be the usual trolley wire. In the drawing, the conductor 2 is illustrated at one side of the track rails for the sake of clarity. It will also be understood, of course, that conductor 2 is connected with one terminal of a source of propulsion current, such as a generator not shown, and the track rails serve as the return path for the propulsion current.

45 This stretch of railway is intersected by a highway H, adjacent which a highway crossing signal S is located. The type of highway crossing signal is immaterial, and as here provided the signal S comprises a green light G and two red lights R and R' , the green light G being normally illuminated to indicate a clear signal when no railway traffic is approaching the intersection, and the red lights R and R' being alternately and periodically illuminated to indicate stop to highway users when a train or car is approaching the intersection on the railway. The signal S is positioned to be displayed to highway traffic approaching the intersection from one direction.

50 In practicing my invention a second signal sim-

55. In practicing my invention, a second signal sim-

ilar to signal S would be located at the intersection and positioned to be displayed to highway traffic approaching the intersection from the other direction. This second signal is not shown for the sake of simplicity since its control would be the same as that of signal S, the control of signal S being fully described hereinafter.

Three traffic governed devices or contactors are associated with this stretch of railway at selected points. These contactors are preferably similar, and in this instance their construction is that of standard practice for trolley contactors. As viewed in the drawing, the contactors C1 and C2 are positioned at selected points to the left and right, respectively, of the intersection. The distance the contactors C1 and C2 are located from the highway is in each case such as to provide satisfactory warning operation of the signal S in response to railway traffic approaching the intersection in the respective directions. To discontinue the operation of signal S, a contact C5 is positioned adjacent the intersection. In other words, a car approaching the intersection from the left, as viewed in the drawing, initiates the warning operation of signal S in passing the contactor C1, and the warning operation is discontinued when the car passes over the highway and operates the contactor C5. A car approaching the intersection from the right initiates the warning operation of the signal in passing the contactor C2, and the warning operation is discontinued when the car passes over the intersection and operates the contactor C5.

Looking at contactor C1, for example, it comprises two contact members 3 and 9 which are juxtaposed with contact member 3 more remote from the intersection. The contact members 3 and 9 are each spaced from the conductor 2 to be normally free from contact therewith. A trolley wheel of a car or vehicle bridges between the conductor 2 and the members 3 and 9 so that current from conductor 2 is applied to the members, current being applied first to member 3 and then to member 9 when a car approaches the intersection, the trolley wheel engaging the member 9 before it leaves the member 3. For a car receding from the intersection, that is, moving from right to left in the drawing, current is first applied to member 9 and then to member 3 of the contactor C1. In a similar manner, the contactor C2 comprises two juxtaposed contact members 5 and 11, the member 5 being more remote from the intersection so that a trolley wheel of a car approaching the intersection applies current first to member 5 and

then to member 11, but a car receding from the intersection causes current to be applied first to member 11 and then to member 5.

- The contactor C5 which is preferably located 5 at the intersection is provided with a single contact member 69 to which current is applied from trolley wire 2 when the trolley wheel of a car moving over the intersection in either direction engages the contact member 69.
- 10 It will be understood, of course, that my invention is not limited to trolley contactors. The important feature of these contactors so far as my present invention is concerned is the fact that contactors C1 and C2 each comprises two 15 contact members to which current is supplied successively and momentarily in response to a car passing thereover, the order in which current is supplied to the two contact members being in accordance with the direction of the passing car.
- 20 For example, in railways other than electric railways, the contact members 3 and 9 of contactor C1 could be actuated by the leading wheel of a 25 passing train, and the source of current could be any suitable wayside source.
- 25 To distinguish between cars approaching the intersection and cars receding from the intersection, a directional device is associated with the first and second contactors C1 and C2. The directional device may take different forms, several 30 being well known. As here provided the directional device comprises a slow releasing neutral relay N6 controlled over a pick-up and a stick circuit, which circuits will be described herein-after.
- 35 The immediate control of signal S is effected by a polarized relay HR, which relay is in turn controlled by the contactors C1, C2 and C5 together with the directional relay N6, relay HR being energized at one polarity when a train is 40 approaching the intersection and being energized at the opposite polarity when the train is receding from the intersection. The relay HR is provided with a normal energizing winding NW and a reverse energizing winding RW, the 45 arrangement being such that when current is supplied to the normal winding NW the polar contact members 96, 103 and 105 of the relay are operated to the left-hand position, that is, the position illustrated in the drawing, contact member 50 105 making engagement with a normal polar contact 106. When current is supplied to the reverse winding RW, the relay HR is energized to move its polar contact members to the right-hand position, where contact members 96 and 55 103 engage reverse polar contacts 97 and 104, respectively. The polarized relay HR is preferably characterized by the fact that the stroke of its polar armature will be completed if energy is applied to either winding for a long enough 60 interval to open the polar contacts in the last position. In other words, when an impulse of current is supplied to winding RW or NW for an interval long enough to move the polar armature from its last position, the polar armature moves 65 to its other extreme position although the energizing current ceases.
- A relay which may be made to operate in the manner just described is disclosed and claimed in Letters Patent of the United States No. 1,790,671 70 granted to Branko Lazich on February 3, 1931, for Electrical relays. In the instant application the polarized relay is provided with two windings disposed for reversibly energizing the relay to operate the polar armature whereas in the patent the relay is shown provided with a single

winding to which current is reversibly supplied for operating the polar armature, such equivalent arrangements for the windings of polarized relays being readily understood by those skilled in the art.

The control circuits for relay HR will be described when the operation of the apparatus is explained.

The lamp G of signal S is controlled over a back neutral contact of relay HR, and the lamps 10 R and 1R of signal S are controlled over front neutral contacts of relay HR through the medium of a flasher relay FR, which flasher relay may be of any of the well-known constructions. It is deemed sufficient for this application to 15 point out that the contact member 56 of relay FR is biased to a mid position, that is, the position illustrated by the solid line in the drawing, and is operated between two extreme positions, illustrated by dotted lines, at a predetermined 20 frequency of, say, 30 times per minute when the winding of the relay FR is energized. As here shown, the contact member 56 engages a contact 25 57 at both its mid and left-hand positions and engages a contact 58 at its right-hand position. For illuminating the lamp G, current is supplied from conductor 2 over wire 92, back neutral contact 93 of relay HR, a resistor R6, lamp G, wires 55 and 70, and to the rail 1b. With relay HR picked up, closing its front neutral contacts, current is supplied from conductor 2 over 30 wire 92, front neutral contacts 98, 99, 100 and 101 in series, wire 63, a resistor R7, winding of flasher relay FR, wires 74 and 70, and to track rail 1b, and the flasher relay FR is operated. 35 During each interval, the contact 56—57 of flasher relay FR is closed, the lamp 1R is short-circuited, and the lamp R is illuminated by current flowing over the same circuit traced for relay FR up to wire 63, and thence over a resistor R8, contact 40 56—57, wire 64, lamp R and wires 55 and 70 to the track rail 1b. During each interval the contact 56—58 of relay FR is closed, the lamp R is short-circuited and the lamp 1R is illuminated by current flowing over the same circuit up to 45 wire 63 and from wire 63 over resistor R8, wire 65, lamp 1R, wire 64, contact 56—58, wires 74 and 70, and to the rail 1b.

In describing the operation of the apparatus, I shall consider the operating steps effected in 50 response to a car moving from left to right. At the start, the lamp G of signal S is illuminated by current supplied over the back contact 93 of relay HR. The trolley wheel of a car approaching the intersection from the left first engages the contact member 3 of contactor C1 to apply current from conductor 2 to member 3, and in so doing causes current to be supplied to the reverse winding RW of relay HR, the circuit involved including contact member 3, wires 4 and 15, back 55 contact 94 of relay N6, wire 95, reverse winding RW, a resistor R14, wire 70, and track rail 1b. I have found that by proportioning the resistor R14 and the winding RW so that the relay HR receives only its normal ampere-turn energization the time constant of the circuit is relatively low and operation of the polar armature of relay HR in less than 0.05 second is effected. With the parts thus proportioned, the relay HR is energized to reverse its polar armature although the 60 winding RW is energized but for the brief interval the contact member 3 is bridged by the trolley wheel. It will be recalled that relay HR is characterized by the fact that its polar armature once started from its last position, will move to 65 70 75

its other extreme position notwithstanding the energizing current ceases. With relay HR reversed, current is supplied over a holding circuit which includes conductor 2, wire 92, reverse polar contact 96-97, reverse winding RW, resistor R14, wire 70, and to the track rail 1b, and relay HR is effectively energized to retain its polar armature at the reverse or right-hand position and to pick up its neutral armature. As the polar armature of relay HR is reversed before the contact member 9 of contactor C1 is engaged by the trolley wheel, a possible circuit, to be later described, for energizing relay N6 is opened at the normal polar contact 105-106 of relay HR. The opening of back contact 93 of relay HR extinguishes the lamp G, and the closing of front contacts 98, 99, 100 and 101 causes current to be supplied to the flasher relay FR, which relay is operated to alternately flash the lamps R and 1R in the manner previously explained.

As this car is moving over the intersection its trolley wheel engages contact member 69 of contactor C5 to cause current to be supplied to the normal winding NW of relay HR, the circuit including contact member 69, wire 102, reverse polar contact 103-104, winding NW, a resistor R15, wire 70 and rail 1b. The resistor R15 and the winding NW are proportioned to provide an ampere-turn energization greater than that effected by the holding circuit energizing winding RW, and also to effect a relatively low time constant for the circuit. The polar armature of relay HR is therefore returned to its normal position in response to the trolley wheel of the car engaging the contact member 69 of contactor C5. With relay HR restored to its normal position, its holding circuit is open at the reverse polar contact 96-97 and relay HR is deenergized to release its neutral armature subsequent to the car passing beyond the contactor C5. The lamps R and 1R are now dark and the lamp G is illuminated. As this car moves to the right its trolley wheel next engages the contact member 11 of contactor C2, and current is supplied from conductor 2 through the contact member 11, wire 12, wire 107, normal polar contact 105-106 of relay HR, wire 108, winding of relay N6, a resistor R16, wire 70, and to the track rail 1b, and the relay N6 is picked up. Relay N6 is supplied with current over a stick circuit when the contact member 5 of contactor C2 is next engaged by the trolley wheel of the car moving away from the intersection, the stick circuit involved including wires 6 and 15, front contact 125 and winding of relay N6, resistor R16, wire 70 and rail 1b. It is to be seen, therefore, that no current is supplied to relay HR when the car moves over the contactor C2 in moving away from the intersection due to the directional control effected by relay N6, the circuit to the RW winding of relay HR being open at back contact 94 of relay N6.

The operation of the apparatus for a car moving from the right to the left is correspondingly similar to that just described for the car moving from left to right. When the trolley wheel engages contact member 5 of contactor C2 current flows over wires 6 and 15, back contact 94 of relay N6, wire 95, reverse winding RW of relay HR, resistor R14, wire 70 and to rail 1b, and relay HR is energized to operate its polar contact members 96, 103 and 105 to the reverse or right-hand position. The holding circuit for relay HR is now closed at reverse polar contact 96-97 so that relay HR is retained at its reverse position and its neutral armature picked up to open back con-

tact 93 and close front contacts 98, 99, 100 and 101. The G lamp of signal S is now extinguished and flasher relay FR operated to flash the stop lights R and 1R. When this car reaches the intersection and the trolley wheel engages the contact member 69 of contactor C5, current is supplied to the normal winding NW of relay HR since the circuit is closed at reverse polar contact 103-104, and the polar contact members of relay HR are operated back to the normal position so that relay HR is deenergized, operation of flasher relay FR and warning indication of signal S ceases, and the G lamp is again illuminated. When the trolley wheel of this car moving from right to left engages contact member 9 of contactor C1, the directional relay N6 is picked up over the circuit including contact member 9, wires 10 and 107, normal polar contact 105-106 of relay HR, wire 108, winding of relay N6, resistor R16, wire 70 and rail 1b. With relay N6 picked up it is retained energized over its stick circuit while the trolley wheel engages contact member 3 of contactor C1, and hence relay HR is not operated as this car recedes to the right from the intersection.

It should be pointed out that in the event a car moving from left to right passes contactor C1 to operate the relay HR to its reverse position and then there is a temporary failure of power to the conductor 2 while the car is between contactor C1 and the intersection, the relay HR is deenergized during the interval of power failure and the warning operation of signal S stops, but relay HR is at once reenergized and picked up over its holding circuit and the warning operation of the signal S is restored as soon as power is restored to conductor 2. A similar action for relay HR is effected in the event of a temporary loss of power while a car moving from right to left approaches the intersection.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track intersected by a highway, a highway crossing signal at the intersection, a first pair of contact members located successively on one side of the intersection, a second pair of contact members located successively on the other side of the intersection, an additional contact member adjacent the intersection, a directional relay, a polarized relay having a normal and a reverse winding, means controlled by the member more remote from the intersection of each of said first and said second pair and including a back contact of the directional relay to supply current to said reverse winding, a holding circuit to supply current to said reverse winding including a reverse polar contact of the polarized relay, means controlled by said additional contact member and including a reverse polar contact of the polarized relay to supply current to said normal winding, a pick-up circuit for said directional relay controlled by the contact member nearer the intersection of each of said first and said second pair and including a normal polar contact of the polarized relay, a stick circuit for said directional relay controlled by the contact member more remote from the intersection of each of said first and said second pair, and operating means including neu- 75

tral contacts of the polarized relay to operate the signal.

2. In combination, a railway track intersected by a highway, a highway crossing signal at the intersection, a first pair of contact members located successively on one side of the intersection, a second pair of contact members located successively on the other side of the intersection, an additional contact member adjacent the intersection, a directional relay, a polarized relay having a normal and a reverse winding, a first circuit means controlled by the member more remote from the intersection of each of said first and said second pair and including a back contact of the directional relay to supply current to said reverse winding to operate the polar armature of said polarized relay to the reverse position, a holding circuit to supply current to said reverse winding including a reverse polar contact of the polarized relay to retain the polar armature at the reverse position and to pick up the neutral armature of the relay, a second circuit means controlled by said additional contact member and including a reverse polar contact of the polarized relay to supply current to said normal winding, said second circuit means effective to create an energization of the polarized relay that overcomes the energization effected by said holding circuit and to operate the polar armature to the normal position, a pick-up circuit for said directional relay controlled by the contact member nearer the intersection of each of said first and said second pair and including a normal polar contact of the polarized relay, a stick circuit for said directional relay controlled by the contact member more remote from the intersection of each of said first and said second pair, and an operating circuit for said signal including a front neutral contact of said polarized relay.

3. In combination, an electric railway provided with a propulsion current conductor and intersected by a highway, a highway crossing signal

at the intersection, a first contactor located to one side of the intersection and including a pair of juxtaposed contact members, a second contactor located at the other side of the intersection and including a pair of juxtaposed contact members, a third contactor located at the intersection and including a single contact member, said contact members disposed to have current applied thereto by the current collector of a passing vehicle, a directional relay, a polarized relay having a normal and a reverse winding, a first circuit to connect said reverse winding between the contact member more remote from the intersection of each of said first and said second contactors and a track rail including a back contact of said directional relay and a first resistor for operating the polar armature of the polarized relay to its reverse position; a holding circuit to connect said reverse winding between said conductor and a track rail including a reverse polar contact of the polarized relay and said first resistor for picking up the neutral armature of the polarized relay, a second circuit to connect said normal winding between the contact member of said third contactor and a track rail including a reverse polar contact of the polarized relay and a second resistor, said second circuit and said holding circuit proportioned that the energization effected by the second circuit overcomes that of said holding circuit to operate the polar armature to its normal position, a pick-up circuit to connect the directional relay between the contact member nearer the intersection of each of said first and second contactors and a track rail including a normal polar contact of the polarized relay, a stick circuit to connect the directional relay between the contact member more remote from the intersection of each of said first and second contactors and a track rail, and an opening circuit for said signal including a front neutral contact of the polarized relay.

PAUL H. CRAGO.
